DESIGN FOR A COMBINED EVENING DRESS AND PANTALOONS

Celia Phillips, New York, N. Y.

Application April 23, 1945, Serial No. 119,134

Term of patent 7 years

(Cl. D3—26)

To all whom it may concern:

Be it known that I, Celia Phillips, a citizen of the United States, residing in New York city, in the county of New York and State of New York, have invented a new, original, and ornamental Design for a Combined Evening Dress and Pantaloons, of which the following is a specification, reference being had to the accompanying drawing, forming part thereof.

Fig. 1 is a front view of a combined evening dress and pantaloons showing my design, and

Fig. 2 is the rear view thereof on a reduced scale.

I claim:

The ornamental design for a combined evening dress and pantaloons, substantially as shown.

CELIA PHILLIPS.
